MUSICAL INSTRUMENT

Filed July 7, 1922

Inventor,
Joseph N. Dwyer,
By Charles J. Schmidt. *File.*

UNITED STATES PATENT OFFICE.

JOSEPH N. VASEY, OF BROOKFIELD, ILLINOIS.

MUSICAL INSTRUMENT.

Application filed July 7, 1922. Serial No. 573,364.

To all whom it may concern:

Be it known that I, JOSEPH N. VASEY, a citizen of the United States, and a resident of Brookfield, in the county of Cook and 5 State of Illinois, have invented certain new and useful Improvements in Musical Instruments, of which the following is a specification.

My invention relates to musical instruments of the string type and covers particularly improved construction and arrangement of the string supporting frame and sounding board structure. In string instruments the strings are usually stretched across 10 the frame at the top thereof to be engaged by the fingers or by striking mechanism, the strings being stretched to the proper tone by means of tuning pins. The heavy tension on the strings has a tendency to warp or bulge 15 the frame. The important object of my invention is to provide a metallic skeleton structure at the bottom of the frame, such structure being secured at one end to the frame and affording anchorage at its other end 20 for the strings. The arrangement is such that the skeleton structure is secured at one end to the frame along the same side that supports the tuning pins, the strings being secured to the other end of the structure and 25 then extending around the edge of the frame and across the top thereof to the tuning pins. When the strings are all stretched and tuned the skeleton structure is under the same tension as the strings and the frame is therefore 30 under uniform strain and will not bulge or warp.

Another important object of the invention is to leave the skeleton structure beyond its secured end free from the frame so that it 35 may vibrate to increase the resonance of the instrument. Another object of the invention is to provide simplified means for anchoring the strings to the skeleton structure.

The above and other features of my invention are incorporated in the construction 45 illustrated on the accompanying drawing, in which—

Fig. 1 is a top view of a string supporting frame.

Fig. 2 is an under side view showing the anchorage and strain equalizing skeleton structure,

Fig. 3 is a sectional view on plane 3—3, Fig. 1, and

Fig. 4 is an enlarged sectional view show-

ing the means for anchoring the strings to the skeleton structure.

The frame shown comprises the longitudinal side beams 5 and 6 and the transverse side beams 7 and 8, intermediate beams 60 or transverse brace members 10 extending between the longitudinal beams 5 and 6. Upper and lower panels 11 and 12 are secured to the beams, the lower panel having the air holes 12' therein.

Secured on top of the frame adjacent to the longitudinal sides thereof are the bridge strips 13 and 14 provided with wire beads 15 on which the strings 8 rest, the strings extending around the spacing pins 16 and to 70 the tuning pins 17. To support the frame in playing position, legs L are provided.

On the under side of the frame is the skeleton reenforcing and balancing structure indicated as a whole by B. This structure 75 comprises transversely extending bars or bands 18 of metal and these bands are secured to the side beam 5 below the tuning pins. To space the bands away from the panel 12 spacer blocks 19 are provided, 80 screws 20 extending through the band and blocks and threading into the side beam 5. At their opposite ends the bands are all secured to the longitudinally extending bar 21 which is close to and parallel with the 85 edge of the side beam 6. The string ends are all anchored to this bar and extend around the edge of the beam 6, and then across the top of the frame to the tuning pins. Wire beads 22 and 23 are applied 90 at the upper and lower corners of the beam 6 against which the strings engage.

In Fig. 4 my improved means for anchoring the strings to the bar 21 is shown. Through the bar 21 are the holes 24 spaced 95 in accordance with the string spacing. Link members 25 having inner and outer hooks 26 and 27 anchor the strings to the bar. The inner hooks of the links are engaged through the holes 24 and the ends of the strings are secured to the outer hooks 27 as clearly shown in Fig. 4. These links can be readily hooked to the bar 21 and the strings can be provided with loops or eyes 28 for readily receiving the links.

If necessary a spacer strip 29 is secured 100 at the lower corner of the side beam 6 to support the wire bead 23 so that when the strings are under tension the bands 18 will be uniformly spaced away from the lower 110

panel 12. When the strings are put under tension by means of the tuning pins such tension will be communicated to the bands 18, the combined tension on the bands being 5 equivalent to the combined tension on the strings, so that the tension across the upper and lower sides of the frame will be equal and humping, bulging and warping of the frame will be prevented. The metallic 10 structure B being secured directly only at one side to the frame and being otherwise clear of the frame, the structure has a chance to vibrate and will thus increase the resonance and sound properties of the frame. 15 By making the structure B of steel it will be very light yet exceedingly strong. The links 25 greatly simplify the assembling. In prior structures anchorage pins had to be driven into the bottom of the frame for the 20 strings. With the links all that is necessary is to hook them to the bar 21 and to the strings and then to turn the tuning pin until the strings have been properly stretched and tuned.

25 I do not desire to be limited to the exact construction and arrangement shown as changes are possible which will still come within the scope of the appended claims.

30 Having described my invention, I claim as follows:

35 1. In a musical instrument, the combination of a frame, a band secured at one end to the bottom of the frame near one edge thereof, a string anchored to the other end of said band and extending around the other edge of said frame and across the top thereof, and a tuning pin receiving the end of said string.

40 2. In a musical instrument, the combination of a string supporting frame, a metal band secured at one end and to the under side of said frame at one edge thereof and extending toward the other edge of said frame, a string anchored to the end of said band and extending around the edge of the frame and across the top thereof and parallel with the band, and a tuning pin at the top of the frame receiving said string.

45 3. In a musical instrument, the combination of a string supporting frame, a metal band secured at one end to the bottom of said frame near one edge thereof and extending to the other edge of said frame, said band being spaced away from said frame, a string anchored to the end of said band and extending around the edge of said frame and across the top thereof parallel with said band, and a tuning pin receiving the end of said string.

50 4. In a musical instrument, the combination of a string supporting frame, a metal band secured at one end to the bottom of said frame at one side thereof, said band being otherwise free and spaced from said frame a distance, a string anchored to the

free end of said band and extending around the edge of said frame and across the top thereof parallel with the band, and a tuning pin receiving the end of the string.

5. In a musical instrument, the combination of a string supporting frame, a plurality of bands secured at one end to the bottom of said frame along one edge thereof and extending parallelly to the other edge of said frame, a bar to which the ends of said bands are secured, strings anchored to said bar and extending around the edge of said frame and across the top thereof parallel with said bands, and tuning pins receiving the ends of said strings.

6. In a musical instrument, the combination of a string supporting frame, metal bands secured at one end to the bottom of said frame along one edge thereof and extending toward the other edge of said frame, a bar adjacent said other edge secured to the end of the bands and having a row of holes, links engaging in said holes, strings secured at one end to said links and extending around the edge of said frame and across the top thereof parallel with said bands, and tensioning pins on said frame receiving the string ends.

7. In a musical instrument, the combination of a string supporting frame, a plurality of bands secured at one end to the bottom of said frame along one edge thereof, said bands extending parallelly toward the other edge of said frame and being spaced from said frame, a bar secured to the ends of said bands, strings connected to said bar and extending around the edge of said frame and across the top thereof, and tuning pins on said frame receiving the string ends.

8. In a musical instrument, the combination of a string supporting frame, a plurality of metal bands extending across the bottom of said frame, a bar connecting said bands at one end, said bands at their other ends being secured to the bottom of said frame but said bar and bands being otherwise entirely free of said frame, strings anchored to said bar and extending around the edge of said frame and across the top thereof parallel with said bands, and tuning pins receiving the ends of said strings.

9. In a musical instrument, the combination of a string supporting frame, a metal band secured at one end to the bottom of said frame at one edge thereof and extending to the other edge of said frame, a tuning pin on the upper side of said frame opposite the secured end of said band, a string engaged by said tuning pin and extending across the frame parallel with said band and around the edge of said frame to the under side thereof, and a link detachably connected with said bands and string for anchoring the string to the band.

10. In a musical instrument, the combination of a string supporting frame, string supporting strips on said frame and tuning pins along one edge of said frame, strings secured to said pins, a plurality of metal bands secured to the under side of said frame below the tuning pins, 20 said bands extending parallelly across the bottom of said frame to its other edge, a bar secured to the ends of said bands and having holes therethrough, links detachably engaging in said holes, and strings extending from 25 said links around the edge of said frame and to said pins, said bands and bar being spaced away from said frame to be free to vibrate.
11. In a musical instrument, the combination of a string supporting frame, string

In witness whereof, I hereunto subscribe 30
my name this 26th day of June, A. D. 1922.

JOSEPH N. VASEY.
